[57] CLAIM

The ornamental design for a combined electronic computer and telephone, as shown and described.

DESCRIPTION

FIG. 1 is a top, front and right side perspective view of a combined electronic computer and telephone showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a left side elevational view thereof;

FIG. 7 is a right side elevational view thereof;

FIG. 8 is a top, front and right side perspective view thereof showing the computer in wall-hanging position;

FIG. 9 is a top, front and right side perspective view thereof showing the keyboard in closed position;

The telephone cord is shown broken away in FIGS. 1-9 for convenience of illustration.
